CLAIM

The ornamental design for a playback device, as shown and described.

DESCRIPTION

FIG. 1 is an isometric view of a playback device. FIG. 2 is another isometric view of the playback device of FIG. 1. FIG. 3 is a side view of the playback device of FIG. 1. FIG. 4 is another side view of the playback device of FIG. 1. FIG. 5 is another side view of the playback device of FIG. 1. FIG. 6 is another side view of the playback device of FIG. 1. FIG. 7 is a top view of the playback device of FIG. 1; and, FIG. 8 is a bottom view of the playback device of FIG. 1. The features shown in evenly broken lines do not form part of the claimed design. Dot-dash broken lines indicate boundaries of claimed surfaces in the design.

1 Claim, 5 Drawing Sheets

Related U.S. Application Data

continuation of application No. 29/510,404, filed on Nov. 26, 2014, now Pat. No. Des. 746,795, which is a continuation of application No. 29/446,524, filed on Feb. 25, 2013, now Pat. No. Des. 721,061.
